(57) **CLAIM**

The ornamental design for a tail light, as shown and described.

DESCRIPTION

FIG. 1 is a front, right, and bottom perspective view of the base of a tail light, showing my new design;

FIG. 2 is a rear, left, and top perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front, right, and bottom perspective view of the cover of the tail light;

FIG. 10 is a rear, left, and top perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof; and,

FIG. 17 is a perspective view of the base and cover of the tail light in an assembled position.

The broken lines in the drawings depict portions of the tail light that form no part of the claimed design.

1 Claim, 17 Drawing Sheets
